UNITED STATES PATENT OFFICE.

EDWIN VAN NOTE, OF HAMILTON, MISSOURI.

TRUSS.

SPECIFICATION forming part of Letters Patent No. 340,067, dated April 13, 1886.

Application filed April 4, 1885. Serial No. 161,226. (No model.)

To all whom it may concern:

Be it known that I, EDWIN VAN NOTE, a citizen of the United States, residing in Hamilton, in the county of Caldwell and State of Missouri, have invented a new and useful Surgical Appliance known as a Truss for Hernia, of which the following is a specification.

The invention is an improvement in trusses, and particularly in that class of such devices in which the pad-arm is pivotally connected with a support and is engaged and actuated by a coiled spring wound on such support, and capable of being set at different points rotarily thereon.

15 The present invention relates particularly to the novel construction whereby the spring may be set and held at different rotary points on the support, to which end it consists in the construction and combination of parts herein-
20 after described.

In the drawings, Figure 1 is a perspective view of my truss, and Fig. 2 is a detail view of the support.

A suitable band, B, has a stem or extension, 25 C, which forms a support for the pad-arm and the spring therefor. The band is formed of metal of sufficient malleability to be bent into any desired shape and of sufficient body to retain such shape, in order to be properly 30 fitted to persons of different shapes or sizes. This support C has its extremity or outer end formed with a non-circular or angular portion, X, and a threaded point, T. At its opposite or inner end the support has a non-circular 35 portion, E. The spring S is formed of wire coiled into shape, and provided between its ends with a loop-bail, L, by which to engage the arm J of pad P. The end coils of this spring are formed non-circular at Y and Z, 40 corresponding to the portions E and X of the support.

The pad-arm is pivoted on the support centrally between portions E and X, and may

be moved longitudinally off or onto such support.

To apply the spring and pad-arm to the support, the spring is slipped endwise thereon until its loop or bail comes opposite the threaded point when the pad-arm is placed on the support, and the remaining half of the spring is applied, the non-circular end portions fitting one on each of the non-circular portions, when the spring may be secured by the nut N.

To set the spring rotarily to different points on the support, it is only necessary to release 55 the fastening-screw, move the spring slightly along the support to detach the engaging non-circular portions, then turn the spring to the desired point, when by moving it onto the non-circular portion it will be thereby held 60 from turning, and may be secured by the nut, as shown.

The construction it will be seen is very simple, and may be made at small cost. By the peculiar formation of the spring, I avoid all 65 attachments thereto which add to the initial cost of such devices, and render them more likely to get out of order by increasing the number of parts, and thus complicating the 70 device.

Having thus described my invention, what I claim, and desire to secure by Letters Patent, is—

A truss substantially as herein described and shown, consisting of the support provided 75 at its opposite ends with non-circular portions E and X, the coil-spring having the coils at its opposite ends formed non-circular and conformed to the portions E and X of the support, and the pivoted pad-arm engaged by said 80 spring, substantially as set forth.

E. VAN NOTE.
